UNITED STATES PATENT OFFICE.

EDWARD T. POLLARD, OF LYNCHBURG, VIRGINIA, ASSIGNOR OF ONE-FOURTH OF HIS RIGHT TO HARRISON W. HOLLY, OF SAME PLACE.

MACHINE FOR MAKING PLUG-TOBACCO.

SPECIFICATION forming part of Letters Patent No. 225,865, dated March 23, 1880.

Application filed November 10, 1879.

To all whom it may concern:

Be it known that I, EDWARD T. POLLARD, of Lynchburg, in the county of Campbell and State of Virginia, have invented a new and 5 useful Improvement in Machines for Making Plug-Tobacco, of which the following is a specification.

The object of the invention is to provide means whereby the tobacco may be fed on the 10 inside of a single belt, rolled in a continuous sheet, and cut into plugs; also, to provide means for keeping clean the surface of the large roll over which the tobacco is carried and the inner face of the belt, all as hereinafter described.

In the drawings, Figure 1 is a plan view of the machine. Fig. 2 is a side elevation. Fig. 3 is a vertical longitudinal section on line $x-x$ of Fig. 1. Fig. 4 is a section of the flanged 20 wheel that carries the belt. Fig. 5 is a detail view, showing the cutter.

Similar letters of reference indicate corresponding parts.

The operative parts of the machine are 25 mounted upon a suitable bed or stand, A, at one side of which is fitted the feeding-table a, and across which is fitted the driving-shaft b, that may be operated by hand or other power. At one end of frame A, and having bearings 30 in the fixed semicircular side plate, c, is a cross-shaft, d, that carries the flanged wheel or roller B. The wheel B is formed with a peripheral gear meshing with a gear-wheel on the shaft b, and is made with a smooth surface, and with 35 one flange, e, adjustable, to vary the distance between it and the fixed flange, the said adjustable flange consisting of a ring applied around the wheel and held by screws, keys, or other suitable devices.

40 Outside of the roller B, and having bearings in the side plate, c, are four or more pressure-rollers, f, which enter between the flanges of roller B. The journals of the rollers f are fitted in slots in plates c radial to the axis of B, and are held down by set-screws g fitted in plates c, whereby the space between rollers f and B may be regulated.

Upon the end of the frame A opposite to roller B a roller, h, is journaled. This roller 45 h is of the same diameter as B, and is held in

sliding boxes adjustable by set-screws k, whereby the distance between the two rollers may be adjusted to regulate the tension of the belt. Around the rollers B h passes an endless belt, l, which is preferably a thin and flexible ribbon of steel, and is of a width to pass snugly between the flanges of the roller B. From one side of plate c depends a spring-arm, m, on the lower end of which is pivoted the scraper and oil and water box n, with its open side 55 60 against the surface of roller B. The arm m should be fitted adjustably, so that the pressure of the box n against the roller may be varied, and the box n is connected to the arm by the pivot-pin n', projecting from the bottom of 65 the box through the arm, whereby the box may be removed for cleaning without the necessity of loosening screw or bolts. The box n serves to keep the surface of roller B clean and wet or oiled. A box, o, of the same kind 70 75 is fitted on an arm, o', from the frame of the machine, to bear beneath the belt l for a similar purpose.

In the side plates, c, above the feed-bed a, is fitted a cross-shaft, q, carrying cone-pulleys 75 q', which are connected by a belt to the cone-pulleys q'' on the driving-shaft b. Between the side arms the shaft q is fitted with eccentrics r and rods r', that connect with the shear-plate s, which is fitted in horizontal slots in 80 side plates, c, whereby the revolution of shaft q reciprocates the plate s to and from roller B. The rods r' carry the cutting-blade t, which has guides t' extending in front of plate s, and by the swing of the eccentric-rods the cutter t 85 is given a vertical movement to and from the plate s, and at the same time the cutter t reciprocates with the plate s. The parts are arranged so that the knife finishes its descent while the parts are moving away from the 90 roller B, whereby the knife will cut and at the same time move forward with the tobacco which passes upon plate s from roller B, as hereinafter described.

The belt l, at its lower side, passes through a 95 trough in the feed-bed a, so that the belt is supported and the trough extends beneath the roller B to the lower pressure-roller, f. The tobacco will be fed upon the belt from bed a, and will be carried between the belt and roller 100

B. The rollers *f* will cause the compression of the tobacco to a continuous strip of uniform size, and the strip will be led off at the top of B to the cutting-plate *s* by the guide *u*, which is fixed above the plate *s*, and extends between the flanges of roller B. The cutter *t* will cut the strip into plugs of uniform size, and the plugs will drop from the plate *s* upon a delivery-slide of any suitable character. The length of the plugs cut can be varied by shifting the belt on the cone-pulleys *q*' *q*² to vary the speed of shaft *q*.

By adjustment of rollers *f* the thickness of the pressed plugs can be varied. In some cases rollers of smaller or larger diameter may be substituted to vary the thickness.

The width of plug is to be regulated by adjustment of the movable ring *e* on roller B, and in changing the width of plug the pressure-

rollers *f* and belt *l* will be removed and others of the required width substituted.

Having thus described my invention, I claim as new and desire to secure by Letters Patent—

1. In tobacco-pressing machines, the revolving shaft *q*, eccentrics *r*, rods *r'*, sliding plate *s*, and cutter *t*, combined with the roller B and belt *l*, substantially as and for the purpose described.

2. In tobacco-pressing machines, the scrapers and boxes *n o*, hung upon spring-arms, in contact, respectively, with the roller and belt, substantially as and for the purpose specified.

EDWARD T. POLLARD.
